UNITED STATES PATENT OFFICE.

MAY L. BURKE, OF NEW LONDON, CONNECTICUT.

NON-REFILLABLE BOTTLE.

1,242,138.

Specification of Letters Patent.

Patented Oct. 9, 1917.

Application filed March 20, 1917. Serial No. 156,145.

To all whom it may concern:

Be it known that I, MAY L. BURKE, a citizen of the United States, residing at New London, in the county of New London, State 5 of Connecticut, have invented certain new and useful Improvements in Non-Refillable Bottles; and I do hereby declare the following to be a full, clear, and exact description of the invention, such as will enable others 10 skilled in the art to which it appertains to make and use the same.

This invention relates to improvements in bottles and particularly to nonrefillable bottles.

15 One object of the present invention is to provide a device which can be inserted in the neck of a bottle and by means of which the outflow of liquid is facilitated while the inflow is prevented.

20 Another object of the present invention is to provide a novel and simple as well as cheap device of this character and one in which attempts to insert a tool for the purpose of holding the valve in open position is 25 effectively prevented.

Other objects and advantages will be apparent from the following description when taken in connection with the accompanying drawing.

30 In the drawing:

Figure 1 is a vertical sectional view through the neck of a bottle, showing my invention in elevation therein.

Fig. 2 is a vertical sectional view taken on 35 the line 2—2 of Fig. 1.

Fig. 3 is a transverse sectional view taken at right angles to that of Fig. 2.

Fig. 4 is a horizontal sectional view taken on the line 4—4 of Fig. 1.

40 Referring particularly to the accompanying drawing 10 represents a metal or other tubular member, on the opposite sides of the upper edge of which are formed the vertically extending arms 11. Cast integrally 45 with the arms are two superimposed disks 12 and 13, the upper one of which is disposed on the upper ends of the arms while the other one is disposed between the arms. In the upper disk, and adjacent one edge, there

50 are formed a plurality of openings or slits 14 for the passage of the contents of the bottle therethrough, while in the lower disk there are formed similar openings 15, adjacent the other edge. Thus the openings of 55 the upper disk are out of vertical alinement

with the openings of the lower disk, thereby preventing the insertion of a wire or other thin tool.

Resting on the upper edge of the tubular portion of the device is a semi-circular plate, 60 the straight edge of which is directed toward the center of the tube, said plate being represented by the reference character 16. Hinged to the straight edge of the plate 16 is a second similar plate 17, the straight edge 65 of which is connected to the straight edge of the first plate, as clearly shown in Fig. 3. The pintle 18 of this hinged connection of the plates extends through the lower portions of said arms, as shown in the drawing. 70 Carried by the central portion of the straight edge of the plate 16 are lugs 19 which engage with the adjacent portion of the plate 17 to prevent the said plate from moving into a position at right angles to the 75 normal closed position thereof. Thus the movable plate, for the plate 16 is secured to the tubular portion and to the arms, is prevented from being held in a wide open position by a tool inserted in the device, and 80 also to prevent the plate from sticking.

Thus when the bottle, in the neck 20 of which the device is properly secured, is inverted the weight of the liquid contents will swing the plate into open position and 85 permit the outflow of said contents. When the bottle is placed in upright position the plate will swing downwardly into closed position on its seat, which is the upper edge of the tubular portion of the device. 90

What is claimed is:

A valved device for insertion in the neck of a bottle including a tubular portion having diametrically opposite and upwardly extending arms, superimposed and oppositely 95 apertured disks disposed in the upper portions of the arms, a stationary semi-circular plate secured to the upper edge of the tubular portion, and a movable semi-circular plate hinged to the first plate and seated on 100 the upper edge of said tubular portion, said stationary plate having a stop lug for engagement with the movable plate.

In testimony whereof, I affix my signature in the presence of two witnesses.

MAY L. BURKE.

Witnesses:

HERMAN KATZ,

CHARLES F. POTTER.
